UNITED STATES PATENT OFFICE.

LEWICKI J. LEON, OF WEST CHICAGO, ILLINOIS.

DESIGN FOR A LOOP FOR BIRD-CAGE STANDS.

Application filed December 12, 1927. Serial No. 24,451. Term of patent 14 years.

To all whom it may concern:

Be it known that I, LEWICKI J. LEON, a citizen of the United States, residing at West Chicago, in the county of Du Page and State of Illinois, have invented a new, original, and ornamental Design for Loop for Bird-Cage Stands, of which the following is a specification, reference being had to the accompanying drawing, forming part thereof.

The figure is a front elevational view of a loop for bird cage stands, showing my new design.

I claim:

The ornamental design for a loop for bird cage stands, as shown.

LEWICKI J. LEON.
